UNITED STATES PATENT OFFICE.

JOHN H. DAVIS, OF LEXINGTON, KENTUCKY, ASSIGNOR TO CHARLES O. HADLY, OF PHILADELHPIA, PENNSYLVANIA.

DESIGN FOR A PHONOGRAPH-RECORD CASE.

57,187.

Specification for Design.

Patented Mar. 1, 1921.

Application filed August 2, 1920. Serial No. 400,866. Term of patent 14 years.

To all whom it may concern:

Be it known that I, JOHN H. DAVIS, a citizen of the United States, residing at Lexington, in the county of Fayette and State of Kentucky, have invented a new, original, and ornamental Design for a Phonograph-Record Case, as shown in the accompanying drawing, forming part of this specification.

In said drawing:

Figure 1 is a view of the case closed.

Fig. 2 is a similar view thereof with the "back" open.

As shown the design resembles in external appearance when closed, as shown in Fig. 1,

an ordinary book; and comprises a substantially rectangular body portion 1 and a rectangular back portion 2, which back forms the door or cover of the book and can be opened, as shown in Fig. 2, for the insertion or removal of the records.

I claim:

The ornamental design for a phonograph record case substantially as shown and described.

JOHN H. DAVIS.
